UNITED STATES PATENT OFFICE.

LAWRENCE E. BAER, OF ATTLEBORO, MASSACHUSETTS, ASSIGNOR TO THE BAER & WILDE COMPANY, OF ATTLEBORO, MASSACHUSETTS.

DESIGN FOR A COLLAR HOLDER.

Application filed December 8, 1927. Serial No. 24,418. Term of patent 14 years.

To all whom it may concern:

Be it known that I, LAWRENCE E. BAER, a citizen of the United States, residing at Attleboro, in the county of Bristol and State of Massachusetts, have invented a new, original, and ornamental Design for a Collar Holder, of which the following is a specification, reference being had to the accompanying drawings, forming part thereof.

I claim:

The ornamental design for a collar holder as shown.

In testimony whereof I have signed my name to this specification.

L. E. BAER.
